(57) **CLAIM**

The ornamental design for a display screen with an animated graphical user interface, as shown and described.

DESCRIPTION

FIG. 1 is a front view of a first image in a sequence for a display screen with an animated graphical user interface; FIG. 2 is a front view of a second image; FIG. 3 is a front view of a third image; FIG. 4 is a front view of a fourth image; FIG. 5 is a front view of a fifth image; FIG. 6 is a front view of a sixth image; FIG. 7 is a front view of a seventh image; FIG. 8 is a front view of an eighth image; FIG. 9 is a front view of a ninth image; and, FIG. 10 is a front view of a tenth image.

The subject matter of this patent includes a process or period in which an image changes into another image. This process or period forms no part of the claimed design. The appearance of the transitional image transitions sequentially between the images shown in FIGS. 1-10.

The outermost broken lines illustrate environmental subject matter. The remaining broken lines illustrate the display screen and portions of the graphical user interface. The broken lines form no part of the claimed design.

1 Claim, 3 Drawing Sheets
